United States Patent Office.

ALEXANDER DICKSON, OF MEADVILLE, PENNSYLVANIA.

Letters Patent No. 80,153, dated July 21, 1868.

IMPROVED UTERINE SUPPORTER.

The Schedule referred to in these Letters Patent and making part of the same.

TO ALL WHOM IT MAY CONCERN:

Be it known that I, ALEXANDER DICKSON, of the city of Meadville, in the county of Crawford, and State of Pennsylvania, have invented a new and improved "Female Uterine Abdominal Supporter;" and I do hereby declare that the following is a full and exact description of the same, reference being had to the accompanying drawings, and letters of reference marked thereon.

Figure 1 represents the inside of my supporter, *i. e.*, the side worn next to the body.

M is a strong band of double cloth or leather, with eyelet-holes at N N for lacing around the body.

This band is divided into five pieces, and the same attached together at C C C C by elastic bands.

A is a large pad, which is placed over the spine.

B B, two smaller pads in front; D D, two straps passing between the thighs, and buckled at E E.

The supporter is worn around the body immediately above the hips.

What I claim as my invention, and desire to secure by Letters Patent of the United States, is—

A uterine supporter constructed in five parts, the same being joined together by the elastic bands C C C C, in combination with the pads B B and A, constructed as described for the purposes set forth.

ALEXR. DICKSON.
